Primary Examiner — George D. Kirschbaum*Assistant Examiner* — Mary Claire Ramirez(74) *Attorney, Agent, or Firm* — Matthias Scholl P.C.;
 Matthias Scholl(57) **CLAIM**

The ornamental design for an electronic cigarette, as shown and described.

DESCRIPTION

FIG. 1 is a front elevation view of an electronic cigarette;
 FIG. 2 is a rear elevation view thereof;
 FIG. 3 is a left-side elevation view thereof;
 FIG. 4 is a right-side elevation view thereof;
 FIG. 5 is a top plan view thereof;
 FIG. 6 is a bottom plan view thereof; and,
 FIG. 7 is a perspective view thereof.
